ROTATABLE TURRET MAGNIFIER

Paul A. Hoogesteger, Brighton, and Kenneth D. Maier, Mendon, N.Y., assignors to Bausch & Lomb Incorporated, Rochester, N.Y., a corporation of New York

Filed Oct. 19, 1964, Ser. No. 82,228

Term of patent 14 years

(Cl. D57—1)

FIG. 1

FIG. 2

FIG. 3

FIG. 1 is a top plan view of a rotatable turret magnifier embodying our new design;

FIG. 2 is a side view thereof; and

FIG. 3 is a perspective view thereof.

The side of the magnifier not shown is substantially like the side shown.

We claim:

The ornamental design for a rotatable turret magnifier, substantially as shown and described.
